BEDPAN OR THE LIKE

Katherine J. Whelan, Los Angeles, Calif.
Application April 2, 1957, Serial No. 45,540

Term of patent 14 years
(Cl. D83—1)

I claim:

The ornamental design for a bedpan or the like, substantially as shown.
